UNITED STATES PATENT OFFICE.

EDWIN M. BEROLZHEIMER, OF NEW YORK, N. Y., ASSIGNOR TO EAGLE PENCIL COMPANY, OF NEW YORK, N. Y., A CORPORATION OF DELAWARE.

DESIGN FOR A SOUVENIR PENCIL.

Application filed June 19, 1925. Serial No. 13,833. Term of patent 7 years.

To all whom it may concern:

Be it known that I, EDWIN M. BEROLZHEIMER, a citizen of the United States of America, residing at New York, in the county and State of New York, have invented a new, original, and ornamental Design for Souvenir Pencils, of which the following is a specification, reference being had to the accompanying drawing, forming part thereof.

Fig. 1 is a front elevation of the souvenir pencil, showing my design;

Fig. 2 is a side elevation of the souvenir pencil shown in Fig. 1.

I claim:

The ornamental design for a souvenir pencil, as shown.

In testimony whereof I hereto affix my signature.

EDWIN M. BEROLZHEIMER.
